CLAIM

The ornamental design for an electronic device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of an electronic device showing our new design;

FIG. 2 is a front view of the electronic device of FIG. 1;

FIG. 3 is a rear view of the electronic device of FIG. 1;

FIG. 4 is a left-side view of the electronic device of FIG. 1;

FIG. 5 is a right-side view of the electronic device of FIG. 1;

FIG. 6 is a top plan view of the electronic device of FIG. 1;

FIG. 7 is a bottom plan view of the electronic device of FIG. 1; and,

FIG. 8 is a rear perspective view of the electronic device of FIG. 1.
